US00D821117S

(12) **United States Design Patent** (10) **Patent No.:** **US D821,117 S**
(45) **Date of Patent:** ** *Jun. 26, 2018

(54) **DISPLAY STRUCTURE**

(71) Applicant: **Apple Inc.**, Cupertino, CA (US)

(72) Inventors: **Michael Gorman**, Dublin, CA (US);
Manuel Reza, Sunnyvale, CA (US);
Federico F. Tio, Santa Cruz, CA (US);
Kevin Fenton Smeds, San Francisco, CA (US); **Edmond Kuan**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/559,270**

(22) Filed: **Mar. 25, 2016**

(51) LOC (11) Cl. **06-04**

(52) U.S. Cl.

USPC **D6/661**

(58) **Field of Classification Search**

(57) **CLAIM**

The ornamental design for a display structure, as shown and described.

DESCRIPTION

FIG. 1 is a top front perspective view of a display structure showing the claimed design;

FIG. 2 is a bottom front perspective view thereof;

FIG. 3 is a front view thereof;

FIG. 4 is a left side view thereof;

FIG. 5 is a right side view thereof; and,

FIG. 6 is a top view thereof.

The dashed broken lines in the figures show portions of the display structure that form no part of the claimed design. The dot-dash broken lines in the figures show boundaries that form no part of the claimed design.

1 Claim, 5 Drawing Sheets
